UNITED STATES PATENT OFFICE.

MARTIN CASTRICUM, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

DELIVERING MOVING WEBS.

Application filed March 6, 1926. Serial No. 92,904.

This invention relates to the handling of moving webs of material such, for example, as the product of a rubber sheeting or coating calender. It is frequently desired to 5 wind up in rolls of definite amount the stock continuously being delivered from a calender. Formerly this has been done by carrying the calendered stock upon a conveyor, above which are a pair of spaced wind-up 10 devices, severing the stock after one of the wind-up devices is full, and starting the leading end of the severed web by hand into the second wind-up device. It is the object of the invention to provide a method and a 15 mechanism for picking up the leading end of the stock without the necessity of the operators touching it with their hands, and to reduce the number of men necessary to operate the wind-up.

20 Referring to the drawings,

Fig. 1 is a side elevation of a wind-up device embodying my invention;

Fig. 2 is a partial top plan of the device; and

25 Fig. 3 is an enlarged sectional detail of a pick-up device.

The calendered web *m* is shown as coming to the wind-up over an equalizing roll 10 and cooling rolls 11. From the cooling rolls 30 the web is received upon a belt conveyor 12, driven in any suitable manner at a speed coordinated with that of the calender. One suitable driving arrangement is shown in my application Serial No. 20,398, filed April 3, 35 1925, jointly with P. L. Butterfield. At 13 is located a cutting device for severing the web entirely across when one wind-up device is full and it is desired to start winding a fresh roll. The cutting device is illustrated as of the type described fully in my 40 joint application with P. L. Butterfield filed November 18, 1925, Serial No. 68,839.

Located on spaced standards 14 are spindles 15, driven by chains 16 from a motor 17, 45 the spindles frictionally engaging wind-up rolls 18. This friction drive forms of itself no part of my present invention and is described in detail in application Serial No. 20,398 above referred to. Also mounted on 50 the standards 14 are spindles 19 which are adapted to carry rolls of a liner material *s*. On short standards 20 is journaled a frame composed of side pieces 21 pivoted to a cross-

shaft 22, joined at one side by a shoe 23 and at the other by a roll 24. A handle 25 on the 55 cross-shaft permits manual rotation of the frame to bring either the shoe or the roll into a position facing the advancing stock.

When the wind-up device is engaged in 60 spooling up stock the liner *s* passes from spindle 19 around roll 24 and over the curved surface 26 of the shoe to the wind-up roll 18. (See the unit at the left in Fig. 1.) The web *m* passes under a roll 27 and joins the liner either at the roll 24 or the shoe 23. 65 Both webs are wound together upon the wind-up roll, the liner acting to prevent adhesion of adjacent turns of the sticky rubberized stock. In case the web *m* is not of an adhesive nature, or is not to be wound 70 up, the liner *s* may be replaced by a short liner sufficient in length to get the stock started upon the wind-up roll.

When a cut has been made the trailing end of the severed web is drawn into the 75 wind-up roll, completing the winding of that roll, while the leading end, indicated at 28 in Figs. 1, 2 and 3, drops upon the conveyor and is carried along by it. Before it has reached the wind-up upon which it is to be 80 spooled, the operator turns the handle of the pick-up frame associated with that wind-up so as to bring the shoe 23, with the liner *s* passing around it, into contact with the belt 12 as shown at the right in Fig. 1 and also 85 in Fig. 3. The travel of the liner *s* being, at the point of contact with the belt, in a direction opposite to the motion of the leading end 28, operates to pick this from the surface of the belt. The direction of motion of 90 the liner is immediately changed, however, by its passage around the end of the shoe (see the arrows in Fig. 3) and carries the web *m* along with it. After the leading end 28 has been fully started the handle 25 is 95 turned to the position shown at the left in Fig. 1, in order to reduce the friction of the liner on the conveyor and around the edge of the shoe.

These operations may be repeated, alternating between the two wind-up devices and at the full speed of the calender, as often as it is desired to change spools. It will be found that in addition to the saving in labor 100 incident to the elimination of the necessity 105 of picking the web *m* off the belt by hand,

a more even lay of the leading end of the stock, a guide roll journaled in the frame and 25 web in the liner will result than is possible with hand operation.

Having thus described my invention, I 5 claim:—

1. A method of picking up stock being delivered on a conveyor belt, which comprises causing a conveying web to pass through an abrupt turn in a direction of motion opposite 10 to that of the belt, and substantially in contact with the belt ahead of the leading end of the stock, whereby the stock will be lifted from the belt and carried upon the web.

2. A pick-up device for stock being delivered 15 on a conveyor belt, which comprises a conveying web, a guide directing the web through an abrupt turn substantially in contact with the belt, and means for causing the web to travel past the guide in a direction opposite to the path of travel of the belt.

3. A pick-up device for stock being delivered 20 on a conveyor belt, which comprises a pivoted frame, a guide member held by the frame and extending across the path of the

stock, a guide roll journaled in the frame and 25 located therein at the opposite side of the pivot, and a conveying web looped around the member and the roll, whereby the frame may be rotated to bring the member or the roll adjacent the belt.

4. A pick-up device for stock being delivered 30 on a conveyor belt, which comprises a pivoted frame, a guide shoe mounted therein and convexed towards the conveyor belt when the frame is rotated so as to bring the shoe 35 closely adjacent the belt, a guide roll journaled in the frame on the opposite side of the pivot from the shoe; and a conveying web passing around the shoe and the roll, all 40 constructed and arranged so that when the shoe is adjacent the belt the web will make an abrupt turn therearound so as to pick up the stock from the belt, and so that when the frame is swung around the roll will travel into position to guide the web and thus relieve the friction of the latter upon the shoe. 45

MARTIN CASTRICUM.
